UNITED STATES PATENT OFFICE.

PETER ZOLL, OF NEWARK, NEW JERSEY.

COMBINED SHOEHORN AND CLAMP.

Application filed September 11, 1924. Serial No. 737,064.

To all whom it may concern:

Be it known that I, PETER ZOLL, a citizen of Germany, residing at Newark, in the county of Essex and State of New Jersey, have invented certain new and useful Improvements in Combined Shoehorns and Clamps; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in shoe-horns; and, the present invention has reference, more particularly, to a novel implement of the general character hereinafter more fully set forth, comprising a main body-member conforming to the shape of the usual shoe-horn, the said body-member being provided with a readily manipulable clamping means, whereby the implement may be attached to an overshoe or rubber, so that the latter can be readily drawn over the shoe, without danger of tearing any portion of the overshoe, and destroying its usefulness.

The present invention, therefore, has for its principal object to provide a novel and simply constructed shoe-horn provided with a clamping means for attachment of the implement to an overshoe or rubber, and the said clamping means serving as a pull-element, whereby the overshoe or rubber is readily pulled over the shoe, worn by the operator, without detriment to the overshoe or rubber.

Other objects of the present invention not at this time more particularly enumerated will be clearly understood from the following detailed description of the present invention.

With the various objects of the present invention in view, the said invention consists, primarily, in the novel shoe-horn hereinafter more fully set forth; and the said invention consists, furthermore, in the novel arrangements and combinations of the various devices and parts, as well as in the details of the construction of the said parts, all of which will be more fully described in the following specification, and then finally embodied in the clauses of the claims, which are appended to and which

form an essential part of the said specification.

The invention is clearly illustrated in the accompanying drawings, in which:

Figure 1 is a pictorial representation of a woman's foot and a shoe thereon, said view showing in connection therewith, in sectional representation, an overshoe or rubber, and in side elevation, a shoe-horn made according to the principles of the present invention, showing its manner of attachment to the overshoe or rubber for pulling the latter over the shoe; and Figure 2 is a detail sectional representation of the devices represented in the said Figure 1, said section being taken on line 2-2 in said last-mentioned figure.

Figures 3 and 4 are views, respectively, of the inner and outer faces of the implement, in said Figure 4, the parts of the clamping means being represented in their clamped relation to the main body-member of the device; Figure 5 is a longitudinal sectional representation of the implement, with the parts of the clamping means represented in their released relation to the main body-member of the device; and Figure 6 is a perspective of the manipulating lever of the implement.

Similar characters of reference are employed in all of the said above-described views, to indicate corresponding parts.

Referring now to the several figures of the drawings, the reference-character 1 indicates a shoe, such as is worn by women, and 2 indicates the usual form of overshoe or rubber adapted to be worn with the shoe, as indicated in Figure 1 of the drawings, the said overshoe or rubber being represented in vertical section in said view.

The herein-mentioned shoe-horn comprises a main body-member or element 3 of the usual shoe-horn configuration, said main body-member having at one end the usual broad inserting-end-portion 4, and being provided at its other end with a suitably formed fingerpiece or pull-member, as 5.

Suitably secured to the outer face of the said main body-member or element 3, by means of rivets 6, or in any other suitable manner, are a pair of members 7, each member being formed with outwardly extending pintle-receiving ears 8.

Pivotedly disposed between these ears 8 is an actuating lever or arm 9, provided at one end with a jaw, as 10, and with oppo-

sitely extending pivot-lugs or pintles 11 which extend into and are oscillatorily disposed in the perforations of the respective ears 8, as will be evident from an inspection of Figures 4 and 5 of the drawings. At its opposite and free end, the said lever or arm 9 is made with a suitably bent or hook-shaped portion 12 which serves as a fingerpiece or lift for the proper manipulation of said lever or arm, as will be evident from an inspection of Figures 1 and 5 of the drawings. Also suitably secured to the outer face of said main body-member or element 3, by means of rivets 13 or 15 in any other suitable manner, at a point between the members 7 and the finger-piece or pull-member 5, is the end-portion 15 of a resilient or spring-like clamping bar or plate 14, the said bar or plate being of suitable length to extend downwardly between and beyond the pintle-receiving ears 8, and beneath the jaw 10 of the lever or arm 9, the action of the said portion of the bar or plate 14, when the jaw 10 is not in active engagement with the said bar or plate being such, that the said portion of the bar or plate will spring outwardly and away from the outer face of the body-member or element 3, so as to produce a receiving space, as 115, as will be clearly seen from an inspection of said Figure 5 of the drawings. Secured to the inner face of the free end-portion of the clamping bar or plate 14 by means of rivets 17 or in any other suitable manner, there may be a gripping pad 16, of a comparatively soft material, such as felt or rubber. It will be understood, however, that this pad may be omitted if desired.

Having in the foregoing described the general construction of my novel shoe-horn and clamping means therefor, I will now briefly set forth the manner of using the implement in connection with an overshoe or rubber for readily drawing the same over the shoe worn by a person. While the implement is capable for use with men's rubbers, it is especially adapted for use in women's rubbers which are difficult to draw over and to properly arrange upon women's shoes, owing to the tight and snug fit desired by women, and owing to the usual high heels with which women's shoes are provided.

Referring now to Figure 5 of the drawings, in using the implement, the arm or lever 9 is brought into the position indicated in said figure, thereby permitting the resilient or spring-bar or plate 14 to move away from the outer surface of the main body-member or element 3, so as to provide the herein-before mentioned receiving space 15.

In attaching the implement to the overshoe or rubber, the rear portion 18 of the

overshoe or rubber is inserted in the space 15, in the manner indicated in said Figure 5, and the arm or lever 9 is swung from the position shown in said Figure 5 to the position represented in Figures 1 and 4. This movement of the arm or lever 9 causes the jaw 10 to ride upon the outer face of the clamping bar or plate 14, thus causing a firm and secure binding or gripping action of the lower end-portion of the said bar or plate 14 and of the pad 16 against the overshoe or rubber, and of the latter against the lower outer surface-portion of the main body-member or element 3. The overshoe or rubber now being securely clamped by the implement, the toe-end of the overshoe or rubber is pulled over the toe-end of the shoe worn by the operator, and by placing the fingers beneath the fingerpieces or pull-members 5 and 12, as indicated in Figure 1 of the drawings, the rear or heel-end of the overshoe or rubber is easily and quickly pulled over the heel of the shoe and properly fitted over the shoe without detriment to the overshoe or rubber.

After the overshoe or rubber has been fitted over the shoe, the arm or lever 9 is again moved into its released position which permits of the combined shoe-horn and clamp to be readily removed, as will be clearly evident.

Of course, I am fully aware that changes may be made in the general arrangements and combinations of the various devices and parts, as well as in the details of the construction of the said parts, without departing from the scope of the present invention as set forth in the foregoing specification, and as defined in the clauses of the claims which are appended thereto. Hence, I do not limit my present invention to the exact arrangements and combinations of the various devices and parts as described in the said specification, nor do I confine myself to the exact details of the construction of the implement, as illustrated in the accompanying drawings.

I claim:

1. A combined shoe-horn and clamp, comprising a main body-member conforming to the conventional form of shoe-horn, a resilient clamping plate secured at one end to said body-member, an arm or lever pivotally mounted upon said body-member, a gripping pad of a soft material at the lower end-portion of said arm or lever, and a clamping jaw extending from said arm or lever adapted to be brought into engagement with said clamping plate for actuating the same and for attachment of the said body-member to an overshoe, or the like.

2. A combined shoe-horn and clamp, comprising a main body-member provided at one end with a fingerpiece and conform-

- ing to the conventional form of shoe-horn, a pair of pintle-receiving ears mounted upon said body-member, an arm or lever provided with oppositely extending pintles 5 for pivotally mounting said arm or lever between said ears, a clamping jaw extending from said arm or lever, a resilient clamping plate secured at one end to said body-member, said plate extending between 10 said ears for engagement of the clamping jaw of said arm or lever with the clamping plate for actuating the same and for attachment of the said body-member to an over-shoe, or the like.
- 15 3. A combined shoe-horn and clamp, comprising a main body-member provided at one end with a fingerpiece and conforming to the conventional form of shoe-horn, a pair of pintle-receiving ears mounted upon 20 the said body-member, an arm or lever
- provided with oppositely extending pintles for pivotally mounting said arm or lever between said ears, a clamping jaw extending from said arm or lever, a resilient clamping plate secured at one end to said body-member, said plate extending between 25 said ears for engagement of the clamping jaw of said arm or lever with the clamping plate for actuating the same and for attachment of the said body-member to an over-shoe, or the like and a gripping pad at the lower end-portion of said clamping plate.
- In testimony, that I claim the invention set forth above I have hereunto set my hand this 8th day of September, 1924.

PETER ZOLL.
